UNITED STATES PATENT OFFICE.

WILLIAM HENRY TROUT, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

FEED-ROLL MECHANISM.

1,309,824.

Specification of Letters Patent. Patented July 15, 1919.

Original application filed March 5, 1910, Serial No. 547,388. Divided and this application filed November 4, 1916. Serial No. 129,903.

To all whom it may concern:

Be it known that I, WILLIAM HENRY TROUT, a citizen of the United States, residing at Milwaukee, in the county of Milwaukee and State of Wisconsin, have invented a certain new and useful Improvement in Feed-Roll Mechanisms, of which the following is a specification.

This invention relates to improvements in the construction of machines used for trimming the edges of sawed lumber, commonly known in lumber-mills as the edger, and has specific relation to improvements in feed roll mechanisms.

An object of the invention is to provide a feed roll mechanism which is simple in construction and efficient in operation. Another object is to provide improved means for adjusting the feed rolls to accommodate various thicknesses of lumber which is to be sawed.

The present application is a division of the application which matured to Patent No. 1,203,940.

A clear conception of an embodiment of the invention may be had by referring to the drawings accompanying and forming a part of this specification, in which like reference characters designate the same or similar parts in the various views.

Figure 1 is an end elevation of an edger having the invention applied thereto.

Fig. 2 is a plan view of an edger having the invention applied thereto.

Fig. 3 is a side elevation of the feed roll driving mechanism, showing the speed-changing device and the shifting-mechanism therefor.

Fig. 4 is a vertical transverse section through a portion of the feed roll mechanism, showing details of the feed roll adjusting means.

Fig. 5 is a transverse vertical section through a portion of the feed roll mechanism showing the feed rolls in their extreme upper position of adjustment.

Fig. 6 is a fragmentary transverse vertical section through the feed roll adjusting cylinder showing the piping for delivering actuating fluid to and discharging the same from the cylinder.

Fig. 7 is an enlarged fragmentary transverse vertical section through the upper part of the feed roll adjusting mechanism.

While the invention is disclosed as applied to a single edger, provided with six saws by way of illustration, it will be understood that the same principles may be applied to double edgers or any other form of saws, without departing from my invention.

The main frame of the edger comprises three transverse frame castings 1, a pair of longitudinally extending channels 2 secured to the frame castings 1, a pair of longitudinal bars 3 preferably formed of double-extra-heavy gas pipes and firmly secured to the castings 1, and a longitudinal shaft 4 also preferably made of double-extra-heavy gas pipe and rigidly secured in long cylindrical sockets formed between the frame castings 1 and suitable caps bolted thereto.

The longitudinal shaft 4 serves as a pivot for the press roll swing arms 20, as will be hereinafter described. While the invention is not restricted to this or any other form of frame, the elements just described provide a simple and rigid frame structure.

The saw shaft 5 is mounted in suitable bearings in the frame castings 1 and has secured thereto a driving pulley 21 of usual form, and a feed roll driving pulley 7 which will be hereinafter described. Upon the shaft 5, set in collars 22, are slidably mounted saws 23, these saws being shiftable by means of saw guides 8 mounted upon the saw-guide carriers 24 which slide upon a longitudinal guide rod 25 the ends of which are mounted in the frame castings 1. The guide carriers 24 are themselves shifted by means of gage mechanisms 26 which slide upon a longitudinal rod 27, this rod also being mounted in the frame castings 1.

Considering now the feed mechanism, a novel arrangement of stepped pulleys for furnishing two rates of speed, is provided. The feed mechanism is as follows: The feed rolls 28 are mounted to rotate in the bearings in the frame castings 1, and are driven from supplementary shafts 12 which are connected with the feed rolls 28 by means of pinions meshing with gears 29 carried by the ends of the feed roll shafts.

On the end of each shaft 12 is mounted a main feed roll driving pulley 30, each of which has two belt faces 31, 32 separated by a conical face 33, see Fig. 2. Coöperating with these pulleys 30 is a smaller pulley 7 previously mentioned, which likewise has two faces, 34, 35 separated by an intermediate conical face 36. Over all three of these pulleys runs a driving belt 37 which also runs around a tightener pulley 10 carried in the bifurcation of a forked bar 40 pivoted upon a pin 41 and weighted at its end opposite to the pulley 10 by means of a sliding weight 42. It will be noted that the position of the pivot 41 relative to the pulley 10 is such as to produce a considerable tension on the belt 37, this tension being practically independent of the position of the belt 37 on one or the other of the two sets of driving faces of the three pulleys, and that in shifting the belt 37 from one set of driving faces to the other, the tightener pulley 10 will move up or down to accommodate the position of the belt 37. In order to permit shifting of the belt 37, a shifting fork 11 sliding in a socket 43 on one of the frame castings 1, is provided, this fork 11 having a pair of downwardly depending prongs 44, one on each side of the belt 37 so that as the fork 11 is moved from one side to the other, the belt 37 will be caused to run on one or the other set of driving faces of the pulleys 30, 7, the tightener pulley 10 varying its position accordingly. To shift the fork 11 a series of rack teeth are cut on the underside of the shaft 41 and a rock shaft 46 is pivoted transversely to the fork in the socket 43, this rock shaft carrying a pinion which meshes with the rack teeth on the shaft 41. The rock shaft 46 is also provided at its free end with a rock arm 47, carrying a weight 48 which acts as a tumble-bob to maintain the belt 37 in the position to which it is shifted, the weight 48 lying on one side of the shaft 46 for one position of the belt and on the other side for the other position.

Considering now the press-roll-operating mechanism, which is shown in detail in Figs. 4, 5, 6 and 7, a fixed cylindrical trunk 50 which may be cored out internally, is mounted in upright position upon the middle of the cross bars 3 by means of supporting lugs 51, the shaft 4 which acts as a pivot for the swing arms of the press rolls 13, also being secured to the trunk 50 by means of a downwardly depending yoke 52. The press rolls 13 are mounted on shafts 53 supported in bearings in the swing arms 20 which as heretofore mentioned swing about the shaft 4 as an axis. Upon the trunk 50 is slidably mounted an upright cylinder 14 which is made steam tight on the periphery of the trunk 50 by means of suitable packing rings. The cylinder 14 has lateral ears 54 for connecting it by means of forked links 55

with the swing arms 20, these links 55 being pivotally connected to the swing arms 20 and having slots 56 at their upper ends through which pass bolts 57 mounted on the ears 54. The lost motion connections afforded by the slots 56 in the links 55, permit limited independent rising of the press rolls 13, due to variations in thickness of lumber passing beneath the rolls. Through the center of the trunk 50 passes a steam pipe 60 which opens into the cylinder chamber 61 past a valve-controlled orifice 62, this pipe 60 connecting at some convenient point with two branch pipes 63, 64 between which and the pipe 60 is located a three-way valve 65. The branch pipe 63 is connected with a source of steam supply while the other branch pipe 64 is an exhaust pipe which may open into the air or lead to a condenser; so that when the handle of the valve 65 is turned to connect the pipe 60 with the branch 63 steam will enter the cylinder chamber 61 and raise the cylinder 14 together with the press rolls 13, thereby permitting the insertion of any size of joist or beam 66 as shown in Fig. 5; and when the lumber has been inserted the handle of the valve 65 may be turned in the opposite direction so as to connect the pipe 60 with the exhaust branch 64, thereby releasing the steam from the cylinder and allowing the press rolls 13 to move downwardly by gravity and to rest upon the beam 66. In order, however, to prevent a sudden drop of the press rolls 13 which would bring undue shock upon the machine, I provide cushioning means in the form of a disk valve 67 which is mounted on the free end of a screw-stud 68 threaded into the head of the cylinder 14 co-axial with the orifice 62. The valve 67 is supported by a head 69 on the stud 68 and is free to move vertically on this stud. When the cylinder 14 reaches a certain point in its descent, predetermined by the position to which the stud 68 is adjusted by the application of a wrench to its upper end, the valve disk 67 will rest upon its seat adjacent the orifice 62, closing this orifice and thereby confining the remaining steam within the cylinder and cushioning the descending cylinder since the steam can then only escape or condense very slowly to permit further downward travel of the cylinder 14. Moreover, a safety device is provided which prevents admission of steam to raise the cylinder 14 beyond a predetermined high point, this safety device being in the form of a relief aperture 70 at the side of the cylinder 14, connected with an exhaust pipe 71 by means of a sliding or telescopic joint 72 consisting of one pipe sliding within the other and connected by a packing so as not to interfere with the continuity of the duct. As soon as the cylinder 14 has risen to the point at which the relief aper-

130

ture 70 is above the upper end of the trunk 50, the steam will escape through the pipe 71 as fast as it flows into the chamber 61, thus limiting the upward movement of the 5 cylinder 14.

While I have hereinabove shown the most improved form of the invention, it should be understood that not all of the features are essential thereto or necessarily made in 10 the exact form shown, but various changes and modifications in the construction as herein shown may be made without departing from the spirit of this invention and it is to be understood, therefore, that the invention is not otherwise limited than by the 15 scope of the appended claims.

It is claimed and desired to secure by Letters Patent:—

1. In combination, means for feeding bodies, a pressing device for urging the bodies against said feeding means, a lever having at one end a fulcrum and associated at its opposite end with said pressing device, and lever manipulating means comprising a 25 power actuated device having a movable portion extending over said lever and means connecting said portion with a medial portion of said lever.

2. In combination, means for feeding bodies, a press roll for urging the bodies against said feeding means, a lever having at one end a fulcrum and connected at its opposite end to said press roll, and fluid pressure actuated lever manipulating means having a 35 movable portion extending over said lever and means connecting said portion with a medial portion of said lever.

3. In combination, means for feeding bodies, a plurality of press rolls for urging the 40 bodies against said feeding means, a lever connected to each of said press rolls, a common pivot about which all of said levers are swingable, and means for swinging said levers about said pivot, said means comprising a power actuated device having a movable portion extending over each of said levers and means connecting each of said portions with the sub-posed lever.

4. In combination, means for feeding bodies, a plurality of press rolls for urging the 50 bodies against said feeding means, a lever connected to each of said press rolls, a common pivot about which all of said levers are swingable, and fluid pressure actuated means for swinging said levers about said pivot, said means comprising a movable portion extending over each of said levers and means connecting each of said portions with the sub-posed lever.

5. In combination, means for feeding bodies, a pressing device for urging the bodies against said feeding means, a lever having at one end a fulcrum and associated at its opposite end with said pressing device, a 60 stationary piston, a cylinder reciprocal

upon said piston, and a connection between said cylinder and a medial portion of said lever.

6. In combination, means for feeding bodies, a press roll for urging the bodies against 70 said feeding means, a lever having at one end a pivot and associated at its opposite end with said press roll, a stationary piston, a cylinder reciprocal upon said piston, means for applying fluid pressure to said 75 cylinder through said piston, and a connection between said cylinder and said lever.

7. In combination, means for feeding bodies, a press roll for urging the bodies against 80 said feeding means, a lever to one end of which said press roll is connected, a fluid pressure actuated cylinder located above said lever and having an axis, a connection between said cylinder and said lever, and a pivot for said lever lying in the plane of the 85 axis of said cylinder.

8. In combination, means for feeding bodies, a press roll for urging the bodies against said feeding means, a lever with one end of which said press roll is associated, a 90] stationary piston, a cylinder slidable upon said piston, a connection between said cylinder and said lever, means for admitting fluid under pressure to said cylinder, and a safety exhaust in the side of said cylinder 95 for relieving the fluid pressure when said press roll reaches a predetermined position.

9. In combination, means for feeding bodies, a press roll for urging the bodies against said feeding means, a pivoted lever 100 with one end of which said press roll is associated, a stationary piston, a cylinder slidable upon said piston, a connection between said cylinder and said lever, means for admitting fluid under pressure to said cylinder 105 and a safety exhaust in said cylinder for relieving the fluid pressure when said press roll reaches a predetermined position in one direction, and means for confining fluid under pressure in said cylinder to cushion 110 said press roll when moving in the opposite direction.

10. In combination, means for feeding bodies, a press roll for urging the bodies against said feeding means, a lever having 115 at one end a pivot and associated at its opposite end with said press roll, a stationary piston, a cylinder slidable upon said piston, a slotted connection between said piston cylinder and a medial portion of said lever, 120 means for admitting fluid under pressure to said cylinder through said piston, a safety exhaust for relieving the fluid pressure when said press roll reaches a predetermined position, and means for cushioning said press 125 roll when moving toward said feeding means.

11. In combination, means for feeding bodies, a pressing device for urging the bodies against said feeding means, means for 130

moving said pressing device transversely of said feeding means, and a lost motion connection for permitting movement of said pressing device independently of said moving means.

12. In combination, means for feeding bodies, a press roll for urging the bodies against said feeding means, fluid pressure actuated means for moving said press roll transversely of said feeding means, and a lost motion connection for permitting movement of said press roll independently of said moving means.

13. In combination, means for feeding bodies, a press roll for urging the bodies against said feeding means, a swinging lever to which said press roll is connected, means for moving said lever and said press roll transversely of said feeding means, and a

lost motion connection for permitting movement of said press roll independently of said moving means.

14. In combination, means for feeding bodies, a press roll for urging the bodies against said feeding means, a lever having at one end a fulcrum and connected at its opposite end to said press roll, fluid pressure actuated means comprising a movable element, and a connection between said fluid pressure actuated means and a medial portion of said lever, said connection permitting relative movement between said lever and said movable element of said actuating means.

In testimony whereof, the signature of the inventor is affixed hereto.

WILLIAM HENRY TROUT.
